UNITED STATES PATENT OFFICE

KARL R. TEMPLETON, OF CHICAGO, ILLINOIS

STORAGE CASE

Application filed October 6, 1928. Serial No. 310,773.

My invention relates to storage cases and has to do more particularly with containers for storing or shipping various kinds of material, which containers are adapted to be securely closed for protecting the contents during shipping or for protection of the contents from dust and the like, while in storage, at the same time being so designed that they may readily and quickly be opened.

10 An object of my invention is to produce a device of the class described which is inexpensive to manufacture, simple in construction, neat in appearance and, at the same time, durable.

15 A further object of my invention is to provide a container in combination with clamping members therefor, said clamping members being positively retained on the container so that no amount of jarring will cause

20 them to loosen or become disengaged.

A still further object is to provide closure members of the type described which will have means for manual engagement thereon in order to facilitate disengaging

25 them from the container.

Many other objects and advantages of the construction herein shown and described will be obvious to those skilled in the art from the disclosures herein given.

30 To this end my invention consists in the novel construction, arrangement and combination of parts herein shown and described, and more particularly pointed out in the claims.

35 Referring now to the drawings forming a part of the specification which illustrate certain preferred embodiments of my invention:

Fig. 1 shows a perspective view of a container embodying my invention;

Fig. 2 is a sectional view taken on line 2—2 of Fig. 1;

Fig. 3 is a sectional view taken on the line 3—3 of Fig. 1;

Fig. 4 is a perspective view of a clamping member forming a part of my invention;

Fig. 5 is a perspective view on an enlarged scale of a securing member forming a part of my invention; and

50 Figs. 6 and 7 are perspective views of mem-

bers similar respectively to those shown in Figs. 4 and 5 and embodying another form of the invention.

Referring now to Figs. 1 to 5 inclusive, the numeral 10 designates a container of any suitable shape, size, material, and design. In its preferred embodiment, however, the container is formed of cardboard, beaver board, or the like, and is in the form of a rectangular parallelopipedon having fixed side walls 11, a bottom wall 12, and top flaps 13 hinged at their edges as at 14. It will be understood that in the type of container shown there is also provided a pair of flaps 16 hingedly connected to the short sides of the container, these flaps underlying the flaps 13. Obviously, other closure means may be substituted for the flaps 13 and 16.

Attached to two of the opposed side walls 11 are securing members indicated generally at 15 and shown in detail in Fig. 5. Each of these securing members comprises a loop portion 17 disposed in spaced relation to the outer face of the side wall of the container and substantially parallel thereto, and tongues 18 disposed on the inside of the container wall. As shown the securing members are provided with the offset portions 17' which will overlie the side wall face of the container. It will be readily understood that the securing members may be stamped in the form shown in Fig. 5, and, when assembled the tongues 18 are passed through the wall of the container, these tongues then being bent or clinched over the main face of the side wall as shown in Fig. 3. Obviously the securing member may be made in various other forms than that disclosed and the tongues may be varied in number and shape as desired. When attached to the container 10, the loop 17 spaced from the container wall forms with the wall of the container the equivalent of a socket.

Clamping members as shown in Fig. 4 are provided for retaining the flaps of the container or other closure in closed position. These clamping members in the embodiment referred to are formed of flat U-shaped strips of comparatively resilient metal, although other suitable material may be used, and

comprise a portion 20 adapted to be disposed transversely of the container and overlie the top and portions 21 forming the legs of the U depending from the portion 20. It will be seen from an inspection of Figs. 2 and 4 that the leg portions 21 in the preferred embodiment are not bent at precisely a right angle from the portion 20, but are at an obtuse angle thereto or slightly spaced outwardly. The purpose of such a construction will later become apparent. Adjacent the extremities of the leg portions 21 are offset portions 23 forming a shoulder, the leg being further extended as shown at 22.

It will be seen that in assembling the clamping members with the container 10 the flaps are placed in the closed position shown in Figs. 1 and 2, and the clamping members are then placed thereover, the leg portions being passed through the loops 17 of the securing members 15. The offset portions 22 of the leg portions 21 of the clamps are urged by the resilient nature of the clamps against the loops 17 as shown best in Fig. 2, the outwardly extending flanges 23 abutting firmly against the lower edge of the loop members 17, so that these clamps are positively retained in the locked position and no amount of jarring in transportation or otherwise can loosen the clamps. When, however, it is desired to remove these clamps the offset portions 22 serve as thumb pieces by which the leg portions of the clamp may readily be pressed inwardly and thus disengage from the loops 17.

If desired to seal in transportation or otherwise, a sticker 25 formed of gummed paper or the like may be pasted over the clamps as shown in Fig. 1. This sticker is not required to maintain the container closed, inasmuch as the clamps alone are sufficient, but serves as a seal, for the clamps cannot be removed without breaking the sticker. This feature, however, is an optional one.

Figs. 6 and 7 show clamping and securing members, respectively, as shown in Figs. 4 and 5, but formed of resilient wire instead of flat material. Obviously the principle of operation in both cases is substantially the same.

Applicant is aware of various devices which are old in the art for retaining in closed position cartons or other packages. One such device comprises a metallic clamp which is adapted to extend over a carton, the ends of the clamp being bent inwardly so as to grip the sides of the carton. Another such device comprises a U-shaped clamp having perforations adjacent its ends, this clamp being adapted to embrace a carton, the side walls of the carton having buttons or pins which are supposed to seat in the perforations of the clamp. The objection to both of the devices described is that the clamps may tend to bend outwardly especially after

repeated application and removal, and unless in perfect order become unseated from the carton, there being no means provided for positively retaining the clamps in retaining position.

In applicant's device, however, the clamps are not only resilient but are so formed that the leg portions spring outwardly rather than at a right angle from the transverse portion thereof, the application tending to spread them and thus these portions are constantly urged against the securing members and undue inward bending prevented by the container wall. These securing members being substantially sockets positively retain the clamps, the clamps being disengageable only by the manual inward depression of the offset portions 22.

Having thus described my invention, it is obvious that various immaterial modifications may be made in the same without departing from the spirit of my invention; for example, if desired, the offset portions 22 may be considerably shortened so that the leg portions 21 terminate merely in the outwardly extending flange 23 adapted to grip the lower face of the loops 17. If this were the case, the clamps could be disengaged from the container merely by pressing inwardly on the ends or the depending portions 21 above the loops 17. It will be noted that the devices are applicable to round or other shaped boxes or containers, as for example wooden cheese boxes, metal containers, etc. Where desired the U-shaped devices may be attached directly to a removable closure. Hence I do not wish to be understood as limiting myself to the exact form, construction, arrangement and combination of parts herein shown and described, or uses mentioned.

What I claim as new and desire to secure by Letters Patent is:

1. In a device of the class described, a container having a bottom wall, side walls and closure means, a resilient U-shaped clamp extending across said closure means and embracing opposed side walls, the legs of said clamp being resiliently urged away from said walls, a loop member attached to each of said walls, and means on said legs releasably engageable by said loop members.

2. In a device of the class described, a container having a bottom wall, side walls and closure means, a resilient U-shaped clamp extending across said closure means and embracing opposed side walls, the legs of said clamp being resiliently urged away from said walls, means on said walls for detachably engaging said legs, means on said legs cooperating with said last-named means, and means on said legs for manually disengaging them.

3. In a device of the class described, a container having a bottom wall, side walls

and closure means, a resilient U-shaped clamp extending across said closure means and embracing opposed side walls, a loop member attached to each of said walls for retaining said clamp and offset portion on the legs of said clamp cooperating with said loop members, and means on said clamp for manually disengaging the same from said loop members.

4. In a device of the class described, a container having bottom, side and end walls and a closure therefor, a resilient U-shaped clamp extending across said closure and having legs provided with offset portions embracing opposite side walls of the container, a loop member attached to each of said side walls and cooperable with said offset portions for retaining the clamp in operative position with respect to said closure and container, and means on said leg portions extending beyond said loop members and removed from the adjacent side of the container for manually disengaging the offset portions from said loop members.

In testimony whereof, I have hereunto signed my name.

KARL R. TEMPLETON.
